4 Claims

ABSTRACT OF THE DISCLOSURE

7 - (*o* - aminomethylphenylacetamido)-3-(1-methyl-5-tetrazolylthio)methyl]ceph-3-em-4-carboxylic acid, 7 - (*o* - aminomethylphenylacetamido)-3-[5-methyl-1,3,4 - thiadiazolylthio)methyl]-ceph-3-em-4-carboxylic acid and 7 - (*o* - aminomethylphenylacetamido)-3-[S-(1,2,3 - triazole-5-yl)-thiomethyl]-ceph-3-em-4-carboxylic acid are valuable as antibacterial agents in animals, including man, and are especially useful in the treatment of infectious diseases caused by many Gram-positive and Gram-negative bacteria. They are administered by injection and for this purpose the preferred formulation, as usual, is a true solution in water. Ordinary methods of converting these water-insoluble zwitterions to a water-soluble salt, such as the sodium salt, require a pH so high that the product is inactivated rapidly and thus cannot be used to formulate an injectable product even when the water is to be added just before use. The present invention solves this problem by converting these cephalosporins to their dimethane-sulfonate sodium salts (containing three atoms of sodium) as by reaction with sodium formaldehyde bisulfite in the presence of sodium 2-ethylhexanoate.

BACKGROUND OF THE INVENTION

(1) Field of the invention

The cephalosporin derivatives of the present invention possess the usual attributes of such compounds and are particularly useful in the treatment of bacterial infections by injection.

(2) Description of the prior art

The three cephalosporins named,

7 - (*o* - aminomethylphenylacetamido)-3-(1-methyl-5-tetrazolylthio)methyl]ceph-3-em-4-carboxylic acid, 7 - (*o* - aminomethylphenylacetamido)-3-[5-methyl-1,3,4 - thiadiazolylthio)methyl]-ceph-3-em-4-carboxylic acid and 7 - (*o* - aminomethylphenylacetamido)-3-[S-(1,2,3 - triazole-5-yl)-thiomethyl]-ceph-3-em-4-carboxylic acid

are disclosed by R. U. Lemieux and R. Raap in U.S. application Ser. No. 142,337 filed May 11, 1971 and issued Oct. 16, 1973 as U.S. 3,766,175. That application also contains a review of the prior art in the field of semi-synthetic cephalosporins.

The literature contains various disclosures of methanesulfonates of antibiotics. Thus Belgium 742,728 (Farm-doc 41466R) discloses the mono-methanesulfonate of ampicillin. U.S. Pats. 3,268,508 and 3,295,246 disclose the conversion of one or more of the four free amino groups of kanamycin to the methanesulfonate derivative. Sodium bacitracin methanesulfonate is disclosed in U.S. 3,205,137 and for neomycin see J. Antibiotics (Japan) 12, 114-115 (1959). The injectable antibiotic colistimethate (marketed by Warner-Chilcott as "Coly-Mycin") is the sodium salt of the methanesulfonate of colistin; Merck Index cites Koyama et al., Japan 4898 (1957). Colistimethate is reviewed in detail on pages 315-320 of the U.S. Dispensatory 26th Edition, J. B. Lippincott Com-

2

pany, Philadelphia, Pa. It is described as the pentasodium salt of the penta(methanesulfonic acid) derivative of Colistin A at pages 621-622 of U.S.P. XVII. U.S. Pat. 2,599,950 in Example VIII discloses "Polymyxin-formaldehyde-sodium bisulfite compound." See also U.K. 874-028, 902,992 and 896,774 and Japan 15,948/61.

SUMMARY OF THE INVENTION

7 - (*o* - aminomethylphenylacetamido)-3-(1-methyl-5-tetrazolylthio)methyl]ceph-3-em-4-carboxylic acid, 7 - (*o* - aminomethylphenylacetamido)-3-[5-methyl-1,3,4 - thiadiazolylthio)methyl]-ceph-3-em-4-carboxylic acid and 7 - (*o* - aminomethylphenylacetamido)-3-[S-(1,2,3 - triazole-5-yl)-thiomethyl]-ceph-3-em-4-carboxylic acid are valuable as antibacterial agents in animals, including man, and are especially useful in the treatment of infectious diseases caused by many Gram-positive and Gram-negative bacteria. They are administered by injection and for this purpose the preferred formulation, as usual, is a true solution in water. Ordinary methods of converting these water-insoluble zwitterions to a water-soluble salt, such as the sodium salt, require a pH so high that the product is inactivated rapidly and thus cannot be used to formulate an injectable product even when the water is to be added just before use. The present invention solves this problem by converting these cephalosporins to their dimethane-sulfonate sodium salts (containing three atoms of sodium) as by reaction with sodium formaldehyde bisulfite in the presence of sodium 2-ethylhexanoate.

There is thus provided by the present invention a compound of the formula

wherein R is

50 The preferred embodiment of the present invention is the compound of the formula

60 There is further provided by the present invention the process for the production of

wherein R is

which comprises mixing a zwitterion of the formula

wherein R is

with at least 2.0 moles of sodium formaldehyde bisulfite per mole of zwitterion, water and at least 2.0 moles of a strong sodium base, e.g. sodium 2-ethylhexanoate in acetone or isopropyl alcohol and warming the mixture above room temperature, e.g. above 40° C. and preferably in the range of 40-45° C., for a brief period of time until there is produced a solution of the desired product. The product is recovered as a solid by precipitation, e.g. by the addition of a water-soluble, substantially anhydrous solvent which is preferably an alcohol such as ethanol or isopropanol.

The use of lesser amounts of sodium formaldehyde bisulfite produces a mixture of unreacted starting material and *di*-methanesulfonate of the present invention; it was unexpected to find that *mono*-methanesulfonate was *not* then produced.

In the treatment of bacterial infections in man, the compounds of this invention are administered parenterally, in accordance with conventional procedures for antibiotic administration, in an amount of from about 5 to 200 mg./kg./day and preferably about 5 to 20 mg./kg./day in divided dosage, e.g., three to four times a day. They are administered in dosage units containing, for example, 125, 250 or 500 mg. of active ingredient alone or, if desired, with suitable physiologically acceptable carriers or excipients or other agents such as preservatives (e.g. parabens) or local anesthetics (e.g. procaine or lidocaine). The dosage units are in the form of liquid preparations and preferably as true solutions in water. The preferred dosage unit is a one-dose vial containing only a sterile amount, e.g. 125 mgm., of a solid compound of this invention. Just prior to use 1 ml. or 2 ml. of sterile water is added to form a solution of the product which is then injected.

DESCRIPTION OF THE PREFERRED EMBODIMENTS

Example 1

4
wherein R represents

wherein R represents

Procedure: Put 2.0 moles (about 952 g. on an anhydrous basis) of 7-(*o*-aminomethylphenylacetamido-3-[(1-methyl-5-tetrazolylthio)methyl]ceph-3-em-4-carboxylic acid, 540 g. of sodium formaldehyde bisulfite (2.03 moles), 3000 ml. of water and 2700 ml. (4.87 moles) of 30% SEH (sodium 2-ethylhexanoate) in acetone in a suitable tank and with stirring heat the mixture to 40-45° C. The mixture dissolves in about 10 min. to a yellow solution.

After 15 minutes of heating add 50 g. of decolorizing charcoal ("Darco KB") to the solution and stir 15 min. more at 40-45° C.

35 Filter through diatomaceous earth ("Dicalite") after heating the reaction at 40-45° C. for a total of 30 minutes.

Wash the carbon cake with 2000 ml. of 50% ethanol-water.

40 Combine the filtrates, adjust to 25° C. and add the solution at 25° C. to 112 liters of rapidly stirred 100% ethyl alcohol. A fine white amorphous precipitate of the *di*(sodium-methane sulfonate) of sodium 7-(*o*-aminomethylphenylacetamido-3-[(1-methyl-5-tetrazolylthio)methyl]ceph-3-em-4-carboxylate forms.

45 Stir the suspension for about 10 minutes and then filter and wash the cake with 15 liters of 100% ethyl alcohol.

50 Dry the cake at 50-55° C. in an oven with air circulating for about 2 hours and then under vacuum at 4-6 mm. for 24 hrs.

55 The yield is about 1200-1400 g. of amorphous, white, solid *di*(sodium-methane sulfonate) of sodium 7-(*o*-aminomethylphenylacetamido-3-[(1-methyl-5-tetrazolylthio)methyl]ceph-3-em-4-carboxylate. The product usually contains several percent water and possibly a trace of ethanol.

Example 2

60 The following slurry is prepared.
2.19 grams of sodium-formaldehyde bisulfite (2-equivalents).

65 3.5 g. of 7-(*o*-aminomethylphenylacetamido-3-[(1-methyl-5-tetrazolylthio)methyl]ceph-3-em-4-carboxylic acid zwitterion (100-200 mesh).

70 25 ml. of water (volume can be varied), 14 ml. of 30% SEH-isopropanol.

A near solution is obtained in about 0.5 hours of rapid stirring at 24° C. The temperature of the mixture is raised rapidly to 40-43° C. This is maintained for about two minutes and then rapidly cooled to 20-23° C.

The solution is filtered to remove some insolubles (total time in solution should not exceed two hours).

The pH 7.3 solution is added over a 5 minute period to 75 600 ml. of very rapidly stirring absolute ethanol (other

alcohols such as anhydrous isopropanol may be used). An amorphous precipitate of the di(sodium-methanesulfonate) of sodium 7-(*o*-aminomethylphenylacetamido)-3-[*(1* - methyl - 5 - tetrazolylthio)methyl]ceph - 3 - em - 4 - carboxylate forms. The mixture is stirred for 5 minutes. The precipitate is collected by filtration, washed with 60 ml. of ethanol (or isopropanol) and vacuum dried at 50° C. for 24 hours. The yield is about 4.3 g.

The product is soluble in water at about pH 7 to the extent of at least 200 mgm./ml. Such a solution is stable for at least two hours at room temperature; more dilute solutions are stable even longer. The product shows the same antibacterial spectrum as the parent zwitterion and is fully biologically active whether it has hydrolyzed back to the zwitterion or not.

Example 3

The following slurry is prepared:

2.19 grams of sodium-formaldehyde bisulfite (2 equivalents).

3.5 g. of 7-(*o*-aminomethylphenylacetamido)-3-[*(5*-methyl - 1,3,4 - thiadiazolylthio)methyl]ceph - 3 - em - 4 - carboxylic acid zwitterion (100-200 mesh).

25 ml. of water (volume can be varied).

14 ml. of 30% SEH-isopropanol.

A near solution is obtained in about 0.5 hour of rapid stirring at 24° C. The temperature of the mixture is raised rapidly to 40-43° C. This is maintained for about two minutes and then rapidly cooled to 20-23° C.

The solution is filtered to remove some insolubles (total time in solution should not exceed two hours).

The pH 7.3 solution is added over a 5 minute period to 600 ml. of very rapidly stirring absolute ethanol (other alcohols such as anhydrous isopropanol may be used). An amorphous precipitate of the di(sodium-methanesulfonate) of sodium 7-(*o*-aminomethylphenylacetamido)-3-[*(5*-methyl - 1,3,4 - thiadiazolylthio)methyl]ceph - 3 - em-4-carboxylate forms. The mixture is stirred for 5 minutes. The precipitate is collected by filtration, washed with 60 ml. of ethanol (or isopropanol) and vacuum dried at 50° C. for 24 hours. The yield is about 4.3 g.

The product is soluble in water at about pH 7 to the extent of at least 200 mgm./ml. Such a solution is stable for at least two hours at room temperature; more dilute solutions are stable even longer. The product shows the same antibacterial spectrum as the parent zwitterion and is fully biologically active whether it has hydrolyzed back to the zwitterion or not.

Example 4

The following slurry is prepared:

2.19 grams of sodium-formaldehyde bisulfite (2-equivalents).

3.5 g. of 7-(*o*-aminomethylphenylacetamido)-3-[*S*-(1,2,3-triazole - 5 - yl)thiomethyl]ceph-3-em-4-carboxylic acid zwitterion (100-200 mesh).

25 ml. of water (volume can be varied).

14 ml. of 30% SEH-isopropanol.

A near solution is obtained in about 0.5 hour of rapid stirring at 24° C. The temperature of the mixture is raised rapidly to 40-43° C. This is maintained for about two minutes and then rapidly cooled to 20-23° C.

The solution is filtered to remove some insolubles (total time in solution should not exceed two hours).

The pH 7.3 solution is added over a 5 minute period to 600 ml. of very rapidly stirring absolute ethanol (other alcohols such as anhydrous isopropanol may be used). An amorphous precipitate of the di(sodium-methanesulfonate) of sodium 7-(*o*-aminomethylphenylacetamido)-3-[*S* - (1,2,3 - triazole - 5 - yl)thiomethyl]ceph - 3 - em - 4 - carboxylate forms. The mixture is stirred for 5 minutes. The precipitate is collected by filtration, washed with 60 ml. of ethanol (or isopropanol) and vacuum dried at 50° C. for 24 hours. The yield is about 4.3 g.

The product is soluble in water at about pH 7 to the extent of at least 200 mgm./ml. Such a solution is stable for at least two hours at room temperature; more dilute solutions are stable even longer. The product shows the same antibacterial spectrum as the parent zwitterion and is fully biologically active whether it has hydrolyzed back to the zwitterion or not.

Starting Materials

Methyl *o*-bromomethylphenylacetate: A mixture of methyl *o*-methylphenylacetate (82.0 g., 0.50 mole), N-bromosuccinimide (89.0 g., 0.50 mole), benzoyl peroxide (1.0 g.) and carbon tetrachloride (800 ml.) was heated under reflux for 2 h. while irradiated with a 750 watt light source. The succinimide was removed by filtration, the solvent removed from the filtrate and the residue distilled *in vacuo* to give 90.1 g. (74%) of product, b.p. 95-105° (0.4 mm.); N.M.R. (CDCl₃): singlets at τ 2.85 (4H), 5.50 (2H), 6.31 (2H) and 6.38 (3H).

***o*-Azidomethylphenylacetic acid:** A mixture of methyl *o*-bromomethylphenylacetate (90.1 g., 0.371 mole), sodium azide (26.0 g., 0.40 mole) and 10% aqueous acetone (750 ml.) was stirred at room temperature for 3 h. The solvent was removed under reduced pressure and the residue treated with ether (300 ml.) and water (100 ml.).

50 The crude methyl *o*-azidomethylphenylacetate (74.8 g.), obtained after drying and concentrating the ether solution, was dissolved in 150 ml. of methanol. This solution was cooled in ice and treated with 150 ml. 3 N methanolic sodium hydroxide. The mixture was left at room temperature for 1 h., then concentrated to dryness and the residue dissolved in water. The aqueous solution was acidified, the product collected by filtration, dried and recrystallized from ethyl acetate-n-hexane to give 49.5 g. (70%) of the acid, m.p. 116-118°; N.M.R. (CDCl₃): sharp singlets at τ 2.75 (4H), 5.63 (2H) and 6.28 (2H);

$\nu_{\text{max}}^{\text{Nujol}}$ 2100 and 1700 cm.⁻¹.

Anal.—Calcd. for C₉H₉N₃O₂: C, 56.53; H, 4.75; N, 21.98. Found: C, 56.37; H, 4.65; N, 21.74.

***o*-Aminomethylphenylacetic acid:** A mixture of *o*-azidomethylphenylacetic acid (9.6 g., 0.050 mole), 10% Pd on charcoal (2.5 g.), methanol (150 ml.) and 1 N hydrochloric acid (50 ml.) was hydrogenated at 30 p.s.i. for 3.5 h. The mixture was filtered, concentrated under reduced pressure to a volume of approximately 30 ml. and extracted with ether. From the ether extract 1-2 g. of impure starting material was recovered. The aqueous solution was adjusted to pH 5.0 with dilute ammonium hydroxide and cooled in ice. The white solid precipitate was collected by filtration, washed successively with ice-water,

methanol and ether, and dried *in vacuo* over P_2O_5 : Yield 5.4 g. (65%), m.p. $179 - 181^\circ$ (decomp.); N.M.R. (CF_3CO_2H): τ 2.54 (s, 4H) 5.48 (q, 2H) and 6.00 (s, 2H).

o-Tert - butoxycarbonylaminomethylphenylacetic acid: Triethylamine (14.4 g., 0.143 mole) was added to an ice-cooled suspension of *o*-aminomethylphenylacetic acid (10.3 g., 0.0624 mole) in 100 ml. of water followed by the addition of a solution of *tert*-butoxycarbonyl azide (11.4 g., 0.080 mole) in 75 ml. of THF. The reaction mixture was stirred at room temperature for 16 h., then most of the THF was removed under reduced pressure. The aqueous solution was washed with ether, layered with 125 ml. of ethyl acetate and with ice-cooling brought to pH 3.5 with dilute hydrochloric acid. The ethyl acetate solution was dried, concentrated and the solid residue recrystallized from ethyl acetate-n-hexane (1:1) to give 14.4 g. (87%) of white needles m.p. 114-116°.

Anal.—Calcd. for $C_{14}H_{19}NO_4$: C, 63.39; H, 7.22; N, 5.28. Found: C, 63.44; H, 7.21; N, 5.42.

2,4-dinitrophenyl-C, 33.4%; II, 7.21%; IV, 5.72%.
2,4-dinitrophenyl-*o*-tert.-butoxycarbonylaminophenylacetate: N,N'-dicyclohexylcarbodiimide (1.0 g., 0.0050 mole) was added to an ice-cooled solution of *o*-tert.-butoxycarbonylaminomethylphenylacetic acid (1.33 g., 0.0050 mole) and 2,4-dinitrophenol (0.92 g., 0.0050 mole) in 12 ml. of anhydrous tetrahydrofuran. The reaction mixture was kept at room temperature for one hour, then the precipitated N,N'-dicyclohexylurea was removed by filtration. The solvent was removed from the filtrate to give the activated ester as a viscous yellow oil.

o-Tert. - butoxycarbonylaminomethylphenylacetic acid can be prepared in quantitative yield from *tert*-butoxycarbonyl azide and the amino acid by using triethylamine as the base.

The BOC-amino acid reacts with thionyl chloride in the presence of triethylamine (methylene chloride as solvent) or pyridine (benzene as solvent) to give the BOC-amino acyl chloride which can be directly coupled with the compound of the formula

wherein R has the meaning set out above in methylene chloride solution in the presence of triethylamine. The protecting group can subsequently be removed by treatment with cold trifluoroacetic acid.

Exactly 200 g. of 7 - aminocephalosporanic acid (7-ACA) was suspended in 500 ml. of acetone and a solution of 240 g. of *p*-toluenesulfonic acid in 500 ml. of acetone was added in one charge. After stirring for five minutes, at room temperature, the mixture was filtered through diatomaceous earth ("Super Cel") and the bed washed with 150 ml. of acetone (the insoluble matter weighed about 30 g.). Then 80 ml. of water was added to the filtrate and, while stirring, the *p*-toluene-sulfonate salt crystallized out after scratching on the inside of the flask with a glass rod. The suspension was stirred in an ice-salt bath for thirty minutes and filtered cold. It was washed with 2 $\times$ 200 ml. of cold acetone (0° C.) and air dried; yield 250 g. of salt. This *p*-toluene-sulfonate salt of 7-ACA was stirred in 2 liters of methanol and the insoluble matter filtered through "Super Cel." The filtrate was placed in a five liter 3 neck flask and 2 liters of water were added. Then the pH was adjusted to 4 by the addition of concentrated ammonium hydroxide with cooling and the suspension stirred for one hour at 0° C. The product was collected by filtration and washed with 2 $\times$ 100 ml. H₂O (0° C.) and 3 $\times$ 1 liter acetone (room temperature). After air drying, the yield of 7-ACA was 145 g.

Reference: Glaxo, British Pat. 1,104,938 (1968).

2-mercaptop-5-methyl-1,3,4-thiadiazole: Lit. ref. U.S. Pat. 3,516,997 (1970); *J. Antibiotics*, 23, 131-36 (1970).

11.5 g. (0.1 mole) of 2-amino-5-methyl-1,3,4-thiadiazole was carefully ground together with 32 g. (0.45 mole) of sodium nitrite and slowly added to 160 ml. of 48% HBr containing 50 mg. of powdered copper at -10°C . with stirring. After the addition was completed, the solution was stirred at -5°C . for one hour and then at 20°C . for one and a half hours. The pH was adjusted to 9.5 by addition of 50% KOH and the solution was heated to 60°C . At 60°C . the pH was readjusted to 9.5 by addition 50% KOH. The solution was cooled and filtered. The precipitate was dissolved in ether and the filtrate was extracted with 2×200 ml. ether. The combined ether solutions were dried over sodium sulfate and evaporated to dryness. The product was recrystallized from benzene-“Skellysolve B.” Yield 12 g., m.p. $105-107^{\circ}\text{C}$.

12 g. (.07 mole) of 2-bromo-5-methyl-1,3,4-thiadiazole and 5 g. (.07 mole) of thiourea were dissolved in 40 ml. of 100% ethanol and refluxed for one and a half hours on a steam bath. This solution was added to 4.5 g. (.08 mole) of KOH in 65 ml. H₂O and the mixture heated to boiling for five minutes. The ethanol was removed under vacuum and the pH of the aqueous solution adjusted to 3 by addition of 3 N HCl. The product crystallized out and after cooling at 0° C. for one hour was collected by filtration, washed with cold water and recrystallized from 100% ethanol. Yield 5 g., m.p. 186-187° C.

Analysis.—Calcd. for $C_3H_4N_2S_2$: C, 27.25; H, 3.05; N, 21.19; S, 48.51. Found: C, 27.20; H, 3.34; N, 21.18; S, 48.48.

7 - amino-3-(5-methyl-1,3,4-thiadiazol-2-ylthiomethyl)-3-cephem-4-carboxylic acid (IIa): To a stirred suspension of 2.72 g. (0.01 mole) of 7-ACA in 50 ml. of 0.1 M, pH 6.4 phosphate buffer, was added 1.68 g. (0.02 mole) of NaHCO₃ followed by 1.45 g. (0.011 mole) of 2-mercapto-5-methyl-1,3,4-thiadiazole and the mixture heated and stirred at 60° C. for five hours. The resulting slurry was then allowed to cool to about 22° C. over a one hour period. The crystalline precipitate was collected by filtration, washed with water and air dried. Yield 1.3 g., dec. pt. 206° C. Scaling up the reaction 10× gave 18.0 g.

Analysis.—Calcd. for $C_{11}H_{12}N_4O_3S_3$: C, 38.37; H, 3.52; S, 27.96. Found: C, 39.06; H, 3.91; S, 26.67.

The synthesis of the thiol was accomplished by a procedure essentially identical to that described in the literature [J. Goerdler and G. Gnad, *Chem. Ber.* **99**, 1618 (1966)].

5-benzamido-1,2,3-thiadiazole: To a stirred solution of benzoylisothiocyanate (50.6 g., 310 mmoles) in commercial anhydrous ether (400 ml.), maintained at 0° and in a nitrogen atmosphere, was added dropwise with vigorous stirring, 0.685 N ethereal diazomethane (453 ml., 310 mmoles). When the addition was completed, the mixture was stirred for 1 hour at 0°, the solid was collected by filtration and dried *in vacuo*. The melting point of the crude material (23.3 g.) thus obtained was observed somewhere in the region 232 to 257°. Goerdler reported m.p. 267° for the pure material. A small second crop (2.1 g.) was obtained by evaporation of the mother liquor *in vacuo*. The total yield was therefore 40%.

1,2,3-triazole-5-thiol: A solution of the above benzamido compound (8.2 g., 40 mmoles) in 2*N* sodium hydroxide (80 ml., 160 mmoles) was heated under reflux temperature in a nitrogen atmosphere for 24 hours. The solution was cooled to 0° in ice, and concentrated hydrochloric acid (26 ml.) was added, while a continuous stream of nitrogen was passed through the solution. The benzoic acid which precipitated was collected by filtration; the filtrate was saturated with sodium chloride and the additional benzoic acid which separated was removed by filtration. The filtrate was immediately extracted with ethyl acetate, the extract was washed with saturated salt solution, dried over magnesium sulfate and then evaporated *in vacuo*. The viscous oil which remained was immediately evaporatively distilled *in vacuo* (70–75°/0.001 mm.) to give an oil (2.84 g., 70%) which solidified (m.p. 52–59°; Goerdeler reported m.p. 60°) spontaneously.

Potassium 1,2,3-triazole-5-thiolate: To a solution of the above thiol (2.84 g., 28.1 mmoles) in absolute ethanol (28 ml.) was added 1.93 *N* alcoholic potassium hydroxide solution (14.5 ml.). The solution was then diluted with anhydrous ether until crystallization of the salt was completed. The solid was collected by filtration, washed with ether, and dried *in vacuo*. The salt obtained in this manner (3.65 g., 93%) had m.p. 225° with decomposition.

It is important to note that the conversion of the benzamido thiadiazole to the triazole thiol is known to proceed via 5-amino-1,2,3-thiadiazole [G. Goerdeler and G. Gnad, *Chem. Ber.* 99, 1618 (1966)].

5-amino-1,2,3-thiadiazole can be prepared by an alternative route, not involving diazomethane [D. L. Pain and R. Slack, *J. Chem. Soc.* 5166 (1965)].

Alternate Synthesis of 1,2,3-Triazole-5-Thiol

Preparation of the starting materials:

O. Diels, *Chem. Ber.* 47, 2183 (1914).

Ethyl Carbazate

60 O. Diels. *Chem. Ber.* 47, 2183 (1914).

Hydrazine hydrate (100%; 44 g.) was added with vigorous stirring over a 10 min. period to diethyl carbonate (100 g.). After a short induction period, the two phase system began to warm up and eventually a clear single phase resulted (ca. 10 min.) The reaction temperature did not exceed 50°. Stirring was continued until a single phase resulted and then the clear solution was set aside for 7 hours (Note 1). The solution was then fractionated *in vacuo* to give a clear liquid b.p. 93.5–95.5°/10 mm. The distillate (70.1 g., 78.7%) crystallized spontaneously on standing.

Note 1. A reaction which was left at room temperature for 16 hours gave precisely the same yield of product.

Phthalimidoacetaldehyde Hydrate

W. Siedel and H. Nahm. Ger. 928,711 (1955); Chem. Abstr. 52, 5471 (1958).

A mixture of dry potassium phthalimide (92.6 g., 500 mmoles) and acetamide (120 g.) was placed in an oil bath maintained at *ca.* 150°. When the acetamide had melted and stirring became possible (Note 1), bromoacetaldehyde diethyl acetal (98.5 g., 500 mmoles) was added to the stirred mixture over a 2 hour period. When the addition was completed, the mixture was stirred at 140° (reaction temperature for 1 hour), then the oil bath temperature was raised to *ca.* 180° (reaction temperature 170°). The reaction temperature was held at 170° for ½ hour, the hot mixture was then poured with vigorous stirring into a large volume of ice-water, the solid was collected by filtration, it was washed well with water, and then sucked as dry as possible. This solid was then stirred vigorously with dichloromethane (600 ml.), the insoluble solid was filtered off, the filtrate was dried over sodium sulfate, treated with a few grams of activated charcoal, filtered, and evaporated *in vacuo*. The residue was broken up, shaken with water and collected by filtration. The solid was pulverized as much as possible while still in the Büchner funnel, it was washed well with water and then dried *in vacuo*. The crude product, m.p. 60–70° (101.8 g., 77.5%), was used in the next step without purification.

The above acetal (90 g.), 85% formic acid (90 ml.) and concentrated hydrochloric acid (9 ml.), were heated together on an efficient steam bath for 20 minutes (Note 2). The hot solution was diluted with water (810 ml.) and the evaporated *in vacuo* (water pump, 30°; Note 3) to a volume of about 150 ml. The mixture was cooled in ice, the solid was collected by filtration, washed with ice-cold water, and then dried *in vacuo*. The white solid thus obtained (65.7 g., 92.4%) melted at *ca.* 90°, resolidified (Note 4), and then melted again at 106–109°. Evaporation of the filtrate and washings as above gave a further 1.1 g. of a solid m.p. 107–158°. It was advisable to recrystallize this material from a large volume of petroleum ether (b.p. 90–120°) containing a trace of benzene. There was thus obtained a further 0.66 g. of product with m.p. 106–109° (Note 5).

Notes

1. It was advisable to stir the mixture mechanically.
2. Shorter heating periods resulted in the recovery of starting material.
3. Higher temperatures gave more of the high melting material described in the text.

12

4. If the melt did not resolidify spontaneously at this stage, the capillary was removed from the melting point apparatus. When the sample had crystallized, it was returned to the apparatus; it then had m.p. 106–109°. This material could be used without purification.

5. The authors (Siedel and Nahm) reported a melting point of 129° for the hydrate. The material with m.p. *ca.* 90° then 106–109° described herein, contains the hydrate as indicated by medium intensity absorptions at 3400 cm^{-1} . The recrystallized material, m.p. 106–109°, is evidently the pure aldehyde. This aldehyde is reported (R. J. Collins, B. Ellis, S. B. Hansen, H. S. Mackenzie, R. J. Moualim, V. Petrow, O. Stephenson, and B. Sturgeon. J. Pharm. and Pharmacol., 4, 693 (1952)) to have m.p. 112°.

Phthalimido Acetaldehyde Ethoxycarbonyl Hydrazone

D. L. Pain and R. Slack. J. Chem. Soc. 5166 (1965).

A solution of ethyl carbazole (38.9 g., 370 mmoles) in warm toluene (300 ml.) was added dropwise to a magnetically stirred solution of the aldehyde hydrate 65.7 g., 317 mmoles) in toluene (600 ml.), containing 3 small crystals of toluene sulfonic acid hydrate, over a 15 minute period. The apparatus was maintained in a water bath at 75° during the addition. When the addition was completed, stirring was continued at 75° (bath temperature) for 3 hours, the mixture was then cooled to room temperature, the product was collected by filtration, and dried *in vacuo*. The white solid (71.0 g., 81.2%) thus obtained had m.p. 160–163° (prior softening), and could be used without further purification. The authors reported that recrystallized material (ethanol) had m.p. 168–169°.

5-Phthalimido-1,2,3-Thiadiazole

D. L. Pain and R. Slack. J. Chem. Soc. 5166 (1965).

Thionyl chloride (66 ml.) was cooled to *ca.* 5° and the hydrazone (60 g., 217 mmoles) was added all at once. The cooling bath was removed, and in a short time a vigorous reaction accompanied by a copious evolution of gases ensued. When this subsided, the mixture was set aside at room temperature for 16 hours (the mixture was swirled occasionally to ensure good contact of the reagents). Benzene (300 ml.) was added to the mixture and the whole was evaporated to dryness *in vacuo*. A

further quantity of benzene was added to the residue and the mixture was evaporated to dryness once more. It was usually necessary to repeat this process one more time to completely remove occluded hydrogen chloride. The solid thus obtained was slurried with benzene, collected by filtration, and dried *in vacuo*. It weighed 40.3 g. (80.4%) and had m.p. 218–221° dec. This material was pure enough to use in the next step, but recrystallization could be accomplished from a large volume of alcohol. It then had m.p. 222–224° dec. The authors reported m.p. 225–226° dec. for the purified material.

5-Amino-1,2,3-Thiadiazole

D. L. Pain and R. Slack, J. Chem. Soc. 5166 (1965).

A solution of hydrazine hydrate (100%, 10.5 g.) in absolute ethanol (150 ml.) was added dropwise to a refluxing, mechanically stirred, mixture of the phthalimido compound (23.1 g., 100 mmoles) in absolute ethanol (320 ml.) over a 1/2 hour period. When the addition was completed, the mixture was stirred under reflux for an additional 1/2 hour. The mixture was cooled to room temperature, the solid phthalhydrazide was removed by filtration, and the filtrate was concentrated *in vacuo* to a volume of ca. 70 ml. The precipitated phthalhydrazide was removed by filtration, washed with a little alcohol, and the combined filtrate and washings were evaporated to dryness *in vacuo*. The residual solid (8.1–10.1 g., 80–100%) was sufficiently pure to be used in the next step. It could, however, be recrystallized from a small volume of alcohol or from a benzene alcohol mixture (3:1) to give a solid m.p. 143–145° dec. The recovery was not good and several additional crops could be obtained by working up the mother liquor. The authors reported m.p. 145–147° for this compound.

1,2,3-Triazole-5-Thiol

J. Goerdeler and G. Gnad, Chem. Ber. 99, 1618 (1966).

A solution of 5-amino-1,2,3-thiadiazole (4.04 g., 40 mmoles) in 2 N sodium hydroxide (40 ml.) was boiled under reflux in a nitrogen atmosphere for 5 minutes. The solution was cooled in ice (nitrogen was bubbled through the solution throughout the workup period), acidified with 10% hydrochloric acid to pH 1 (indicator paper), saturated with salt, and then extracted as rapidly as possible with ethyl acetate. The extract was dried briefly over magnesium sulfate (nitrogen was bubbled through the extract) and then evaporated *in vacuo*. The residual oil was immediately (Note 1) subjected to evaporative distillation (80°/0.001 mm.) to give a clear distillate which crystallized spontaneously. The yield of the pure thiol varied between 64 and 84% depending on the purity of the starting thiadiazole.

Note 1. In the crude state, the thiol is very sensitive to aerial oxidation to the disulfide. The purified thiol possesses considerably more stability and can be kept at 0° in stoppered vessels for several weeks without significant change.

7-amino-3-[S-(1,2,3-triazole-5-yl)-thiomethyl]-3-cephem-4-carboxylic acid: Ten grams (0.075 mole) of 5-mercaptop-1,2,3-triazole potassium salt was added to a stirred slurry of 19 g. (0.07 mole) of purified 7-aminocephalosporanic acid and 5.9 g. (0.07 mole) of NaHCO₃

in 350 ml. of 0.1M phosphate buffer (pH 6.4) and the mixture heated and stirred at 55° C. for 3 1/2 hours under a nitrogen atmosphere. The resulting solution was cooled to 22° C. and the pH adjusted to 5.5 with 40% H₃PO₄. The resulting precipitate was filtered off, washed with cold water (50 ml.) and air dried. The yield of 7-amino-3-[S-(1,2,3-triazole-5-yl)-thiomethyl]-3-cephem-4-carboxylic acid was 8 g., dec. pt. 230° C. Ir analysis showed some decomposition of the β-lactam ring but it was used "as is" for the next step.

Anal.—Calcd. for C₁₀H₁₁N₅O₃S₂: C, 38.39; H, 3.54. Found: C, 38.36; H, 3.78.

7-amino-3-(2-methyl-1,3,4-thiadiazole-5-thiomethyl)-3-cephem-4-carboxylic acid: As disclosed in South Africa 70/2,290, to a stirred mixture of 27.2 g. (0.1 mole) of 7-aminocephalosporanic acid in 200 ml. of water and 100 ml. of acetone was added a saturated solution of sodium bicarbonate to a pH of 7.9. This solution was placed in an 80° C. bath and when the internal temperature had reached 45° C. a solution of 19.6 g. (1.15 mole) of 2-methyl-1,3,4-thiadiazole-5-thiol in 200 ml. of acetone was added. The mixture was heated in the 80° C. bath for three hours and then cooled in 10° C. and the pH was adjusted to 3.9 by the addition of 6 N hydrochloric acid. The cold mixture was stirred for 15 minutes and the solid was collected, washed with acetone, and dried. There was obtained 24 g. (70 percent) of 7-amino-3-(2-methyl-1,3,4-thiadiazole-5-thiomethyl)-3-cephem-4-carboxylic acid.

7-amino-3-(1-methyl-1,2,3,4-tetrazole-5-thiomethyl)-3-cephem-4-carboxylic acid: The above preparation was repeated using 1-methyl-1,2,3,4-tetrazole-5-thiol instead of the thiadiazole. There was obtained 25 g. (76 percent) of 7-amino-3-(1-methyl-1,2,3,4-tetrazole-5-thiomethyl)-3-cephem-4-carboxylic acid. The preparation of this same compound is also described in U.S. Pat. 3,516,997 in column 6 under the heading "Preparation 7."

15
EXAMPLE A

7-(*o*-aminomethylphenylacetamido)-3-[*(1*-methyl-1,2,3,4,-tetrazol-5-thio)methyl]-ceph-3-em-4-carboxylic acid

N,N'-dicyclohexycarbodiimide (1.44 g., 0.0070 mole) was added in one portion to an ice-cooled solution of *o-tert*-butoxycarbonylaminomethylphenylacetic acid (1.86 g., 0.0070 mole) and 2,4-dinitrophenol (1.29 g., 0.0070 mole) in 15 ml. of ethyl acetate. The mixture was kept at 0° for 30 min., then at 25° for an additional 30 min. The precipitate was removed by a filtration and the solvent removed from the filtrate. To the crude activated ester was added, at 0°, a solution of 7-amino-3-[(1-methyl-1,2,3,4-tetrazol-5-thio)methyl]ceph-3-em - 4 - carboxylic acid (2.30 g., 0.0070 mole) and triethylamine (1.41 g., 0.014 mole) in 15 ml. of methylene chloride. The reaction mixture was stirred at room temperature for 2 hours, a small amount of insoluble material was removed by filtration and the filtrate diluted with ether. The oily precipitate was twice redissolved in a small amount of methylene chloride and reprecipitated with ether. It was then dissolved in a small amount of methanol and this solution treated with 3.5 ml. of a 2.3 M solution of potassium 2-ethylhexanoate in *n*-butyl alcohol. Ether was added and the precipitated potassium salt of the protected cephalosporin (2.2 g.) was collected by filtration. An aqueous solution of the potassium salt was layered with ethyl acetate and, with stirring, acidified to pH 2.5. The ethyl acetate layer was dried and concentrated to give the cephalosporanic acid as a foam (1.3 g.). This was treated, at 0°, for one hour with 10 ml. of trifluoroacetic acid followed by the addition of ether. The precipitate was collected, washed with ether, and dissolved in a mixture of water (20 ml.) and acetone (20 ml.). The pH was adjusted to 5.0 with dilute ammonium hydroxide. Then the solution was concentrated under reduced pressure to a small volume and cooled. The product precipitated and was collected by filtration and washed with ice-water, methanol and ether respectively, yield 0.45 g. (14%). The infrared and n.m.r. spectra fully agreed with the assigned structure; the purity was estimated at 85%.

EXAMPLE B

7-(*o*-aminomethylphenylacetamido)-3-[(5-methyl-1,3,4-thiadiazolylthio)methyl]ceph-3-em-4-carboxylic acid

The cephalosporin was prepared by the same procedure given in detail in Example A but using 7-amino-3-[(5-methyl-1,3,4-thiadiazolylthio)methyl]ceph-3-em-4-carboxylic acid. The purity of the product obtained was estimated at 90%; infrared maxima (Nujol mull): 3300 (NH), 1765 (β -lactam carbonyl and 1660 cm^{-1} (amido-carbonyl).

EXAMPLE C

7-(*o*-aminomethylphenylacetamido)-3-[S-(1,2,3-triazole-5-yl)thiomethyl]-ceph-3-em-4-carboxylic acid

This cephalosporin is prepared by the same procedure given in detail in Example A but using an equimolar weight of 7-amino-3-[S-(1,2,3-triazole-5-yl)thiomethyl]-ceph-3-em-4-carboxylic acid.

Samples of 7-(*o*-aminomethylphenylacetamido)-3-[(1-methyl-5-tetrazolylthio)methyl-ceph-3-em - 4 - carboxylic acid (called New Cpd. No. 1) and 7-(*o*-aminomethylphenylacetamido)-3-[(5-methyl-1,3,4 - thiadiazolylthio)-methyl]ceph-3-em-4-carboxylic acid (called New Cpd. No. 2) after solution in water and DMSO respectively followed by dilution with Nutrient Broth were found to exhibit the following Minimum Inhibitory Concentrations (M.I.C.) in mcg./ml. versus the indicated microorganisms as determined by overnight incubation at 37° C. by Tube Dilution. Results with cephalothin are also given.

*50% nutrient broth, 45% antibiotic assay broth.

45 7 - (*o* - aminomethylphenylacetamido)-3-[(1-methyl-5-tetrazolylthio)methyl-ceph-3-em-4-carboxylic acid and 7-
 46 (*o*-aminomethylphenylacetamido)-3-[(5 - methyl - 1,3,4-thiadiazolylthio)methyl]ceph-3-em-4-carboxylic acid were
 well absorbed in mice upon parenteral, but not oral, administration. A lower minimum dose (CD₅₀) of each of
 50 these two compounds than of cephalothin was required by subcutaneous administration in two doses to cure 50% of
 groups of mice infected with *E. coli* Juhl (A15119). Example A, 7 - (*o* - aminomethylphenylacetamido)-3-[(1-methyl-1,2,3,4-tetrazol-5-thio)methyl]-ceph-3-em - 4 - carboxylic acid is also named 7-(*o*-aminomethylphenylacetamido) - 3 - [(1-methyl-5-tetrazolylthio)methyl]-ceph-3-
 55 em-4-carboxylic acid.
